UNITED STATES PATENT OFFICE.

JOSEPH W. LARISH, OF NEW YORK, N. Y., ASSIGNOR TO R. H. SELLERS COMPANY, OF NEW YORK, N. Y., A CORPORATION OF NEW YORK.

AUTOMATIC TELEGRAPHY.

1,182,849.

Specification of Letters Patent.

Patented May 9, 1916.

Application filed April 26, 1913. Serial No. 763,753.

To all whom it may concern:

Be it known that I, JOSEPH W. LARISH, a citizen of the United States, residing in the borough of Manhattan, city, county, and ⁵ State of New York, have invented a certain new and useful Improvement in Automatic Telegraphy, of which the following is a specification.

This invention relates primarily to automatic or machine telegraphy of the kind in which perforated transmitting tapes are used. It may, however, be usefully applicable in other relations.

In automatic telegraphy, the perforated transmitting tape traverses between opposed contacts that meet through the perforations and so transmit into the line successive signal impulses.

It is the purpose of this invention to electrically improve such contacts which ordinarily are made and broken with great rapidity.

In some automatic systems, it has been proposed to employ a single contact connected to the line and in others, two such contacts. The latter is the arrangement employed in the Delany system. The line contact is usually placed above the tape and bears upon it so that when a perforation arrives opposite the contact the latter passes through the perforation into electrical connection with the coöperating contact beneath the tape. Of course, the line contact might be beneath the tape and the coöperating contact above it. These suggestions are all applicable to the present invention.

The accompanying drawing shows the invention in a form which experience has demonstrated to be practical and highly efficient.

Figure 1 is a longitudinal section on the line A, B of Fig. 2; Fig. 2, a section on the line C, C of Fig. 1; Fig. 3, a partial plan.

The wheel or rotating contact member, ⁴⁵ in the construction illustrated, comprises a metal bushing 1 having a flange head 2 by which it may be attached to a shaft 3. Over the bushing contiguous to the head is an insulating disk 4 against which is held a hub ⁵⁰ 5 of insulating material which has a central radial flange 6 on the respective sides of which are driven or tightly seated on the hub annular metal contact rings 7, 8. On the shaft outside the hub is an insulating ring 9 and the parts are set up against the

flange 2 by a nut 10 applied to the threaded end of the bushing. The contact rings 7, 8 have peripheral faces flush with that of the flange 6 and upon such flat surfaces may bear contacting brushes 15, connected with the transmitter battery or source of energy. At the inner edge of each of the conducting rings 7, 8, is a raised annular rib 11. A perforated transmitting tape 12 passes over and partly around the wheel contact just described. This tape is shown as having parallel series of perforations. The tape is of such width as to be conveniently guided between the insulating washers 4, 9, and the parallel series of perforations are so spaced as to overlie the annular ribs 11. In line with the perforations and hence in line with the ribs 11 there are elastic fingers 13, 13, which may be electrically connected together and to line. Each of the fingers 13 is made up of a plurality of conducting wires of suitable elasticity. This is seen in Fig. 1 which shows four wires in each brush 13. There may be more or only three. The width across the ends of these brushes should be a trifle less than the diameter of the perforations in the tape; and the annular conducting ribs 11 at their base lines should preferably be not of greater width than the diameter of the perforations in the tape.

A contact member having a raised continuous rib, such as 11, is in its best form, circular. It may run as an idler and be rotated by frictional contact with the perforated tape drawn over it; or it may be driven and if desired coöperate in the feed or drawing of the transmitting tape. The object of this organization is to obtain clean electrical contact. That is effected by the character of the contact surfaces. The elastic separate strands or wires of the brush tend to press through the perforations against the annular rib 11, and act upon the rib to keep it burnished and in good condition for electrical contact because the elastic wires will slip laterally downwardly across or along the sides of the rib maintaining its surface in favorable condition for contact with the individual wires.

Heretofore in automatic telegraphy, the maintenance of conditions favorable to good electric contact has been difficult to secure and much trouble has been experienced in the practical operation of such systems employing perforated tapes. The construction

herein described has been exhaustively tried out in practical commercial use which has demonstrated that it eliminates the various contact troubles heretofore forming an objectionable incident to the operation of such systems in rapid telegraphy.

I claim:

1. A rotatable contact member for automatic electrical transmission provided with 10 an annular contact rib in combination with a contact brush engaging said rib on its opposite sides.
2. A rotatable contact member for automatic electrical transmission provided with 15 an annular contact rib curved convexly in cross-section in combination with a contact brush engaging said rib on its opposite sides.
3. In automatic electrical transmission, a contact member convexly formed to engage 20 a wire brush in combination with a wire brush, the wires of which are separated laterally by the convex member which engages the sides of the wire as the perforated tape passes between the brush and contact member.
4. A contact member having a continuous annular rib curved convexly in cross-section and adapted to be in line with a series of longitudinal perforations in a trans-

mitting tape and a coöperating contact 30 brush also adapted to be in line with said perforations and with said ribs said brush being composed of a plurality of small resiliant electrical conductors tending to pass through perforations in the tape into contact with the middle portion and also the sides of the convexly curved surface of said rib to thus make good electrical contact therewith and to clean or burnish it.

5. In automatic telegraphy, a rotatable 40 contact member having a peripheral continuous convexly curved contact rib adapted to be in line with a series of perforations in a transmitting tape and a coöperating contact brush composed of a plurality of elastic attenuated conductors which by their resilience tend to pass through the perforations in a tape into contact with the middle portion and also the sides of the convexly curved surface of said rib to thus make good electrical contact therewith and to clean or burnish it.

In testimony whereof, I have hereunto subscribed my name.

JOSEPH W. LARISH.
